WASHING MACHINE

Warren O. Manley, North Kansas City, Mo., assignor to C. Earl Hovey, trustee, Kansas City, Mo.

Application November 27, 1950, Serial No. 13,135

Term of patent 14 years

(Cl. D49—1)

To all whom it may concern:

Be it known that I, Warren O. Manley, a citizen of the United States, residing at North Kansas City, in the county of Clay and State of Missouri, have invented a new, original, and ornamental Design for a Washing Machine, of which the following is a specification, reference being had to the accompanying drawing, forming a part thereof.

Fig. 1 is a front end perspective view of a washing machine, showing my new design; and,

Fig. 2 is a rear perspective view thereof.

I claim:

The ornamental design for a washing machine, as shown.

WARREN O. MANLEY.
